UNITED STATES PATENT OFFICE.

FRANK B. LOCKTON, OF NEW YORK, N. Y., ASSIGNOR TO DEXTER FOLDER COMPANY, OF PEARL RIVER, NEW YORK, A CORPORATION OF NEW YORK.

PAPER-FEEDING MACHINE.

1,237,348.

Specification of Letters Patent. Patented Aug. 21, 1917.

Application filed August 15, 1916. Serial No. 114,991.

To all whom it may concern:

Be it known that I, FRANK B. LOCKTON, a citizen of the United States, and resident of New York, in the county and State of New York, have invented certain new and useful Improvements in Paper-Feeding Machines, of which the following is a specification.

This invention relates to feeding machines embodying sheet-engaging instrumentalities such for example as combing wheels which are periodically movable into and out of engagement with the top sheet of a pile and according to which the sheet-feeding action is regulated by varying the pressure exerted by the sheet-feeding instrumentality and in connection with suitable sheet-actuated means for terminating the period of action of said instrumentality. The primary object of this invention is to provide improved means for applying additional pressure to the combing instrumentalities and in changing the relative pressure on said sheet-feeding instrumentalities for straightening the sheet. More specifically stated, one of the objects of my invention is to provide an improved construction, combination and arrangement of parts in a device of this character in virtue of which the mechanism for applying additional pressure to laterally spaced combing wheels, equalizes the additional pressure between said combing wheels as long as they are both active but automatically applies the entire additional pressure to one of said combing wheels as soon as the other combing wheel is raised from the pile under the action of sheet-controlled means. In this way the distribution of additional pressure to the sheet-combing wheels is regulated by the period of comb of said wheels. Other and further objects will appear in the specification and be pointed out in the appended claims, reference being had to the accompanying drawings, in which my invention is exemplified and in which,

Figure 1 is a side elevation of a preferred embodiment of my invention under normal working conditions, parts being shown in section;

Fig. 2 is a front elevation of the same;

Fig. 3 is a rear elevation of the same;

Fig. 4 is a view similar to Fig. 1 showing parts thereof in different positions;

Fig. 5 is a view similar to Figs. 1 and 4 showing some of the parts in changed positions to which they have been moved from the positions shown in Fig. 4.

Referring more particularly to the drawings, a pile of sheets 1 is suitably mounted to have the positions of the forward edges 55 of the different sheets determined by vertical bars or guides 2, having forwardly deflected slightly upturned portions 3 over which said sheets are fed one by one by means of laterally spaced combing wheels 4 60 which are journaled on shafts 5 carried in the outer ends of lever arms 6. Two of the lever arms 6 are shown in Fig. 3. Each lever arm 6 is provided with a hub portion 7 keyed to separately movable sleeves 8 65 which are journaled on a common shaft 9. The sleeves 8 are independently oscillated under the control of sheet actuated means (not shown) which determines the period of comb for the purpose of straightening a 70 sheet. It will be understood also that said combing wheels are usually raised at periodic intervals independently of said sheet-actuated means, the latter means ordinarily becoming effective before the periodically 75 operated means. Not infrequently, however, it happens that the full period of comb is not sufficient to advance the top sheet of a pile into position to be fed off. In Patent No. 1,165,521, granted to me on December 28th, 1915, I have described and claimed means for applying additional pressure to a 80 combing wheel for increasing the amount of feed that is given to the top sheet of a pile. The present application contemplates improved means for effecting the same object. Referring now to Fig. 3, each of the shafts 5 projects inwardly from the inside lever arm 6 which helps to support it. Rigidly secured to each of the shafts 5 is a bracket 90 85 10. In the right hand bracket 10, one end of a rod 11 is journaled by means of a pin 12. The other end of rod 11 is slidably mounted in a cylindrical block 13 having reduced ends 14 journaled in the left hand 95 bracket 10. An arm 15 which is mounted on the rod 11 intermediately of the brackets 10, is connected to a spring rod 16 to which is threaded an adjustable abutment 17 between which and the cylindrical block 18 in 100 which the upper end of rod 16 slides, is

interposed a spring 19 which imparts a yieldable additional pressure to the combing wheels 4, 4 under the action of mechanism to be presently described. The cylindrical 5 block 18 is provided with a stud 20 which is rotatably mounted in the boss 21 on the upper end of a lever 22, being retained therein by a nut 23. Lever 22 is journaled on a stud 24 threaded into a bracket support 25. The other arm of lever 22 is pivotally connected at 26 with the upper end of a connecting rod 27, the lower end of said rod being pivotally connected at 28 to one arm of a lever 29 which is pivoted at 30 on the 10 bracket support 25. The other arm of lever 29 carries a pin 31 which is adapted under certain predetermined conditions to be engaged by a hook 32 on a detachable link 33. The link 33 is pivotally connected at 34 to the depending end of a cam lever 35, which is journaled on a stud 36 carried by the bracket support 25. The cam lever 35 carries a pin or stud 37 upon which is journaled a cam roller 38 which travels over the peripheral surface of a cam 39 keyed to a cam shaft 40. The cam shaft 40 rotates continuously and thereby imparts a periodic reciprocation to the detachable link 33. Another cam 41 is for the most part circular 15 but contains a peripheral recess 42, which under certain predetermined conditions permits a cam roller 43 carried by a cam lever 44, to move inwardly toward the cam shaft 40. Cam levers 35 and 44 are provided with yieldable means (not shown) for drawing said levers toward their respective cams. Cam lever 44 is oscillatable preferably about the axes of a stud 45, the hub 46 of said cam lever being provided with a downwardly 20 and rearwardly projecting arm 47 upon which a dog or finger 48 is pivotally mounted at 49, being acted upon by a spring 50 which tends to draw it up under the detachable link 33 into a position which, under certain predetermined conditions, to be presently referred to, lifts the detachable link 33 sufficiently to prevent the hook 32 coming into engagement with the pin 31 when the link is reciprocated. The rear and lower end of the arm 25 47 carries a pendulum 51 which is adapted to swing about a pivot 52 when acted upon by a sheet in the manner to be presently described. By an inspection of Figs. 1, 4 and 5, it will be noted that the forwardly presented portion of the guide bar 2, is provided with a recess 53 which is suitably arranged to accommodate the pendulum 51 when a sheet is not present to prevent said pendulum assuming a vertical position 30 under the action of gravity. Immediately in front of the recess 53 is a plate or table 54 which is adapted to prevent the downward displacement of the pendulum 51 whenever said pendulum is displaced by a sheet when the forward edge of said sheet

reaches a point within a predetermined distance of the drop rollers (not shown). The operation of the machine will now be readily understood and briefly related as follows:

During the periodic rise and fall of the combing wheels 4, the detachable link 33 is reciprocated in the manner hereinbefore referred to. While this is going on, the periodic oscillation of cam arm 44 produces a rise and fall of the pendulum 51 within the recess 53 unless said pendulum has been displaced by the forward edge of the top sheet as shown in full lines in Fig. 1, according to which a downward movement of the pendulum will be prevented by the fixed plate or table 54. Whenever this occurs the pendulum 51 rests upon the plate or table 54 during the time that the cam roller 43 is passing over the recess 42 in cam 41 after which said cam 41 by again coming into engagement with the cam roller 43, lifts pendulum 51 slightly away from plate or table 54 and permits the sheet to throw said pendulum into dotted line position shown in Fig. 1. This is what happens during the normal operation of the machine when the co-operative action of laterally spaced combing wheels straightens the top sheet while bringing its forward edge up to within a certain predetermined distance of the drop rollers. The spring 50 acts to hold the dog or finger 48 against a stop 55 on the hub 46 of cam lever 44, thereby preventing the detachable link 33 from dropping into engagement with the pin 31 during the next rearward movement of link 33. Hence the normal action of the combing wheels proceeds under a substantially constant pressure. It frequently happens however, from one cause or another, the sheets do not feed as freely as necessary, for a proper operation of the machine. In this event, the top sheet leaves the recess 53 open for the pendulum to swing into vertical position over said recess. In consequence, when the cam roller 43 next reaches a position opposite to the recess 53, it drops into said recess since the dog or finger 51 is not supported by plate or table 54. Thereupon the parts assume the positions shown in Fig. 4, the detachable link 33 having dropped into engagement with the pin 31. During the next rearward movement of the link 33, the parts are made to assume the relative positions shown in Fig. 5, according to which the spring 19 has been compressed to apply additional pressure to the combing wheels. By an inspection of Fig. 3, it will be noted that this additional pressure will be applied to the rod 11 and hence equally distributed to the oppositely arranged combing wheels. Obviously when either of said combing-wheels is raised which takes place automatically when the forward edge of the top sheet on that side reaches a predetermined posi-

tion, the entire additional pressure is thrown on to the other combing wheel and the combing action on that side made stronger to hasten the straightening of the sheet. As the rearward movement of detachable link 5 33 takes place spring 50 permits the dog or finger 48 to be displaced as shown in Fig. 5.

I claim:

1. In a sheet feeding machine, the combination of a sheet feeding instrumentality adapted to exert a normally constant pressure on the top sheet of a pile, means for applying additional pressure to said instrumentality, including an element suitably disposed to be moved by a sheet into inoperative position when said sheet is normally fed by said sheet feeding instrumentality, and to move by gravity into operative position when said sheet is insufficiently fed by 20 said sheet feeding instrumentality.

2. In a machine of the character described, a feeding instrumentality adapted to exert a normally constant pressure on the top sheet of a pile, of periodically operated means for applying additional pressure to said instrumentality, including an element normally adapted to assume a position permitting the operation of said additional pressure applying means and to be moved 25 by said top sheet into a position to prevent the operation of said additional pressure applying means when said sheet has reached a predetermined point in its travel.

3. In a machine of the character described, a feeding instrumentality adapted to exert a normally constant pressure and means for applying additional pressure to said instrumentality including an element displaced by the feeding movement into a position to render the additional pressure applying means 40 inoperative.

4. In a machine of the character described, a feed board provided with an aperture, a feeding instrumentality adapted to exert a normally constant pressure and means for applying additional pressure to said instrumentality, including a pendulum suitably suspended to hang normally over said aperture and in the line of feed, said pendulum 50 being adapted to be displaced by a sheet into a position in which it will be supported by a part fixed with respect to said feed board.

5. In a machine of the character described, a feed board provided with an aperture, a feeding instrumentality adapted to exert substantially constant pressure upon sheets to be fed successively over said feed board and means for applying additional pressure to said instrumentality, including a member 55 disposed above said feed-board and which rises and falls relatively thereto, together with a pendulum suspended from said rising and falling member and normally held by gravity in position to enter said aperture, said pendulum being arranged in the

line of feed and adapted to be displaced by the movement of a sheet, into a position in which it will rest upon said feed board for blocking the downward movement of said member.

6. In a sheet - feeding machine, a sheet-feeding instrumentality adapted to exert a normal pressure upon the top sheet of a pile, of additional pressure-applying means rendered operative by an insufficient feed movement to said top sheet, such insufficient feed movement and the application of additional pressure to said instrumentality to overcome this insufficiency being produced within the period of one and the same sheet-feeding operation.

7. In a sheet - feeding machine, a sheet combing instrumentality, and means for automatically changing the pressure exerted by said instrumentality, including a pendulum suitably disposed to be engaged by a sheet to be moved into a position to prevent the operation of said pressure changing means.

8. In a sheet - feeding machine, a sheet-feeding instrumentality movable into and out of engagement with the top sheet of a pile under normally constant pressure, of means for applying additional pressure to said instrumentality, and means normally holding said additional pressure means inoperative, said holding means including a sheet-controlled pendulum, which is suitably disposed to be displaced by the forward edge of a normally fed sheet into position to be 100 supported by a rigid portion of the machine.

9. In a sheet - feeding machine, a sheet-feeding instrumentality movable into and out of engagement with the top sheet of a pile under normally constant pressure, of means for applying additional pressure to said instrumentality and means normally holding said additional pressure means inoperative, said holding means including a sheet-controlled pendulum, and a vibratory 110 member from which said pendulum is suspended, said pendulum being normally sustained by a sheet for preventing the vibratory movement of said member.

10. In a machine of the character described, a sheet - feeding instrumentality movable into and out of engagement with the top sheet of a pile under normally constant pressure, means including detachably connected elements for changing the pressure on said instrumentality and a sheet-actuated pendulum for controlling the connection between said elements.

11. In a machine of the character described, a sheet - feeding instrumentality movable into and out of engagement with the top sheet of a pile under normally constant pressure, means including detachably connected elements for increasing the pressure exerted by said instrumentality, and

sheet-controlled means for moving one of said elements into and out of operative connection with the other.

12. In a machine of the character described, a sheet-feeding instrumentality movable into and out of engagement with the top sheet of a pile under normally constant pressure, means including detachably connected elements for increasing the pressure exerted by said instrumentality, and means adapted to be actuated by said top sheet after a predetermined amount of feed has been imparted thereto, for disconnecting said elements.
13. In a sheet-feeding machine, a sheet-feeding instrumentality movable into and out of engagement with the top sheet of a pile, a power driven shaft, an instrumentality for applying additional pressure to said sheet-feeding instrumentality, a mechanical train connecting said power shaft with said additional pressure applying instrumentality, said train including an element movable into and out of power transmitting position in said train, and sheet-controlled means for moving said element into and out of power transmitting position.
14. In a sheet-feeding machine, a sheet-feeding instrumentality movable into and out of engagement with the top sheet of a pile, a power driven shaft, an instrumentality for applying additional pressure to said sheet-feeding instrumentality, a mechanical train connecting said power shaft with said additional pressure applying instrumentality, said train including an element movable into and out of power transmitting position in said train, and sheet-controlled means for moving said element into and out of power transmitting position, said sheet-controlled means including a periodically operated lever provided with means for engaging said movable element.
15. In a sheet-feeding machine, a sheet-feeding instrumentality movable into and out of engagement with the top sheet of a pile, a power driven shaft, an instrumentality for applying additional pressure to said sheet-feeding instrumentality, a mechanical train connecting said power shaft with said additional pressure applying instrumentality, said train including an element movable into and out of power transmitting position in said train, and sheet-controlled means for moving said element into and out of power transmitting position, said sheet-controlled means including a cam arm carrying a movable finger for engaging said movable element.
16. In a sheet-feeding machine, a sheet-feeding instrumentality movable into and out of engagement with the top sheet of a pile, a power driven shaft, an instrumentality for applying additional pressure to

said sheet-feeding instrumentality, a mechanical train connecting said power shaft with said additional pressure applying instrumentality, said train including an element movable into and out of power transmitting position in said train, and sheet-controlled means for moving said element into and out of power transmitting position, said sheet-controlled means including a cam arm provided with means for engaging said movable element, and a sheet-actuated pendulum suspended from and controlling the movement of said cam arm.

17. In a machine of the character described, a sheet-combing wheel movable into and out of engagement with the top sheet of a pile, said combing wheel being adapted to exert a normally constant pressure, means for applying additional pressure to said combing wheel, including a reciprocatory power driven rod and an element detachably connected therewith, a sheet actuated pendulum, means for raising and lowering said pendulum with respect to the line of feed of said sheet, said pendulum being adapted to be moved by the forward movement of said sheet, into a position in which its downward movement is blocked by a portion of said machine, and means connected to said pendulum for detaching said reciprocatory rod when the downward movement of said pendulum is blocked.

18. In a machine of the character described, a sheet-combing wheel movable into and out of engagement with the top sheet of a pile, said combing wheel being adapted to exert a normally constant pressure, means for applying additional pressure to said combing wheel, including a reciprocatory power driven rod and an element detachably connected therewith, a sheet actuated pendulum, means for raising and lowering said pendulum with respect to the line of feed of said sheet, said pendulum being adapted to be moved by the forward movement of said sheet, into a position in which its downward movement is blocked by a portion of said machine, and means connected to said pendulum for detaching said reciprocatory rod when the downward movement of said pendulum is blocked, said detaching means including an oscillatory member carried by the means for raising and lowering said pendulum.

19. In a machine of the character described, a combing wheel movable into and out of engagement with the top sheet of a pile under a normally constant pressure, of a mechanical train of elements for applying additional pressure to said combing wheel, including a reciprocatory power-transmitting rod detachably connected up in said train, a vertically oscillatable lever, a sheet actuated pendulum suspended from

- said lever and an oscillatable finger carried by said lever for engaging said reciprocatory rod.
20. In a machine of the character described, a combing wheel movable into and out of engagement with the top sheet of a pile under a normally constant pressure, of a mechanical train of elements for applying additional pressure to said combing wheel, including a reciprocatory power-transmitting rod detachably connected up in said train, a vertically oscillatable lever, a sheet actuated pendulum suspended from said lever and an oscillatable finger carried by said lever for engaging said reciprocatory rod, said finger being provided with means for yieldably holding it in engagement with said reciprocatory rod.
21. In a machine of the character described, laterally spaced sheet feeding instrumentalities movable into and out of engagement with the top sheet of a pile, said sheet feeding instrumentalities being adapted to normally exert a substantially constant pressure on said sheet, sheet-controlled additional pressure-producing means, and means for equalizing the additional pressure between said sheet feeding instrumentalities.
22. In a machine of the character described, laterally spaced sheet-feeding instrumentalities movable into and out of engagement with the top sheet of a pile, said sheet feeding instrumentalities being adapted to exert a normally substantially constant pressure on said sheet, and means for jointly applying additional pressure to said sheet-feeding instrumentalities.
23. In a machine of the character described, laterally spaced sheet feeding instrumentalities movable into and out of engagement with the top sheet of a pile, said sheet feeding instrumentalities being adapted to normally exert a substantially constant pressure on said sheet, sheet-controlled additional pressure-producing means, and means for equalizing the additional pressure between said sheet-feeding instrumentalities, said equalizing means including a member movably connected to each of said sheet-feeding instrumentalities, said additional pressure producing means applying its pressure to said sheet-feeding instrumentalities by means of said member.
24. In a machine of the character described, laterally spaced sheet-feeding instrumentalities adapted to normally exert substantially constant pressure, a rod or bar movably connected to both of said sheet-feeding instrumentalities, and sheet-controlled means for applying pressure to said rod or bar.
25. In a machine of the character described, laterally spaced sheet-combing wheels capable of being raised and lowered independently under the control of opposite edges of a sheet, shafts upon which said combing wheels are mounted, a pressure transmitting block carried by each of said shafts, a connecting rod movably connected to each of said pressure blocks to permit relative movement between said combing wheel shafts, and sheet-controlled means for applying pressure to said connecting rod.
26. In a machine of the character described, laterally spaced combing wheels capable of being raised and lowered independently of each other, and means common to both of said combing wheels for applying pressure to said combing wheels while permitting each of said combing wheels to be raised and lowered independently of each other.
27. In a machine of the character described, laterally spaced sheet-feeding instrumentalities capable of being raised and lowered independently of each other, said instrumentalities normally exerting a substantially constant pressure, and sheet-controlled means common to both of said sheet-feeding instrumentalities for applying additional pressure thereto.
28. In a machine of the character described, laterally spaced sheet-facing instrumentalities capable of being raised and lowered independently of each other, said instrumentalities normally exerting a substantially constant pressure, and sheet-controlled means common to both of said sheet-feeding instrumentalities for applying additional pressure thereto, said additional pressure-applying means being adapted to automatically increase the additional pressure on one of said sheet-feeding instrumentalities when the other one is raised from the sheet which is being fed.
29. In a machine of the character described, laterally spaced sheet-feeding instrumentalities adapted to exert normally constant pressure and to be raised from the top sheet of a pile independently of each other, and sheet-controlled means common to both of said instrumentalities for applying additional pressure to either of said instrumentalities without interrupting the movement of the other instrumentality from a pile of sheets.
30. In a machine of the character described, laterally spaced sheet-feeding instrumentalities adapted to exert normally constant pressure and to be raised from the top sheet of a pile independently of each other, and sheet-controlled means common to both of said instrumentalities for applying additional pressure to either of said instrumentalities without interrupting the movement of the other instrumentality from a pile of sheets, said additional pressure-applying means being adapted to equalize

the pressure on said sheet-feeding instrumentalities as long as both are acting upon a sheet.

31. In a machine of the character described, laterally spaced sheet-feeding instrumentalities adapted to exert normally constant pressure and to be raised from the top sheet of a pile independently of each other, and sheet-controlled means common to both of said instrumentalities for applying additional pressure to either of said instrumentalities without interrupting the movement of the other instrumentality from a pile of sheets, said additional pressure applying means being adapted to exert all of its pressure on one of said feeding instrumentalities when the other sheet-feeding instrumentality is raised from the sheet.
32. In a machine of the character described, laterally spaced sheet-feeding instrumentalities, each adapted to exert substantially normally constant pressure on the top sheet of a pile, means for applying additional pressure to said top sheet by means of either of said sheet-feeding instrumentalities depending upon the position of said top sheet.

33. In a machine of the character described, laterally spaced sheet-combing instrumentalities adapted normally to exert a substantially constant pressure on the top sheet of a pile and common means for applying additional pressure to said sheet-combing instrumentalities, said means being adapted to equalize the additional pressure between said sheet-combing instrumentalities.

34. In a machine of the character described, laterally spaced sheet-combing instrumentalities adapted normally to exert substantially constant pressure on the top sheet of a pile, and means for applying additional pressure to said sheet-combing instrumentalities, said additional pressure applying means being adapted to apportion the additional pressure between said sheet-combing instrumentalities depending upon the relative periods of comb of said instrumentalities.

FRANK B. LOCKTON.
